DESCRIPTION

Notice: more than one reissue application has been filed for the reissue of U.S. Pat. No. D671,940. This design patent application is a reissue of U.S. Design Pat. No. D671,940, issued Dec. 4, 2012, which claims the benefit under U.S.C. Sections 119 and 172 of Korean Patent Application Serial No. 30-2011-0031692, filed Jul. 29, 2011, which is hereby incorporated by reference in its entirety into this application.

FIG. 1 is a front perspective view of a mobile phone monitor showing my new design;

FIG. 2 is a front view [of the mobile phone monitor of FIG. 1] thereof;

FIG. 3 is a rear view [of the mobile phone monitor of FIG. 1] thereof;

FIG. 4 is a left-side view [of the mobile phone monitor of FIG. 1] thereof;

FIG. 5 is a right-side view [of the mobile phone monitor of FIG. 1] thereof;

FIG. 6 is a top [plan] view [of the mobile phone monitor of FIG. 1] thereof;

FIG. 7 is a bottom [plan] view [of the mobile phone monitor of FIG. 1] thereof; and,

FIG. 8 is a rear perspective view of the mobile phone monitor of FIG. 1, in which a mobile phone [shown] in broken lines [for environmental purposes only and forms no part of the claimed design illustrates] is provided to illustrate an example of how the mobile phone may be [docketed in] docked to the mobile phone monitor of FIG. 1.

The broken lines in the figures show portions of the mobile phone monitor which form no part of the claimed design.

The broken line showing of the mobile phone in FIG. 8 is for environmental purposes only and forms no part of the claimed design.
